(57) **CLAIM**

The ornamental design for a refill for a ball-point pencil as shown and described.

DESCRIPTION

1.1: a perspective view of a first embodiment of a refill for a ball-point pencil showing our new design;

1.2: a front view thereof;

1.3: a back view thereof;

1.4: a left view thereof;

1.5: a right view thereof;

1.6: a top view thereof;

1.7: a bottom view thereof;

1.8: an enlarged left side view thereof;

2.1: a perspective view of a second embodiment of a refill for a ball-point pencil showing our new design;

2.2: a front view thereof;

2.3: a back view thereof;

2.4: a left view thereof;

2.5: a right view thereof;

2.6: a top view thereof; and

2.7: a bottom view thereof; and

2.8: an enlarged left side view thereof.

(Continued)

Broken lines show environmental features that form no part of the claimed designs. The dash-dot broken lines in the drawings show only the boundary of the claim.
